UNITED STATES PATENT OFFICE

WILLIAM H. REISNER, OF HAGERSTOWN, MARYLAND, ASSIGNOR TO THE W. H. REISNER MANUFACTURING COMPANY, OF HAGERSTOWN, MARYLAND, A CORPORATION OF MARYLAND

VALVE FOR ORGANS AND THE LIKE

Application filed April 18, 1929. Serial No. 356,185.

My invention relates broadly to valves for organs and the like, and more particularly to a construction of magnetic valve for organs.

One of the objects of my invention is to provide an improved valve construction for organs having means for accurately guiding and housing an armature member which forms the valve closure within the valve structure whereby the armature is confined within a predetermined space.

Another object of my invention is to provide an organ valve construction having means to retain the armature thereof and prevent the armature blowing away when the plate containing the valve is removed from magnet base while under pressure of wind from the organ wind chest.

Still another object of my invention is to provide a construction of magnetic valve for organs wherein a disc type armature is provided having one surface area of magnetic material and an opposite surface area of fibrous material, the fibrous material being securely retained in position with respect to the magnetic material forming one side of the armature.

A further object of my invention is to provide a construction of magnetic valve for organs in which means are provided for guiding and housing a movable armature member within the valve structure for maintaining the armature in alignment with the actuating electro-magnets and eliminating substantially all noise due to valve movement heretofore experienced in organ valves.

A still further object of my invention is to provide an assembly of magnetic valve for organs in which a minimum number of metallic parts may be secured together to form a housing for a movable armature member wherein means are provided for accurately centering and guiding the movable armature member with respect to the magnetic poles of the actuating electromagnets.

Other and further objects of my invention reside in the construction of the magnetic valve described in the specification herein-after following and shown in the accompanying drawings in which:

Figure 1 is a side elevation of the valve structure of my invention; Fig. 2 is a plan view of the valve structure shown in Fig. 1; Fig. 3 is a horizontal sectional view on line 3—3 of Fig. 1; Fig. 4 is a central vertical longitudinal section through the valve structure on line 4—4 of Fig. 2; Fig. 5 is a horizontal sectional view on line 5—5 of Fig. 4; Fig. 6 is a transverse vertical section on line 6—6 of Fig. 4; Fig. 7 is a perspective view of one form of the parts constituting the armature guiding means; Fig. 8 is a perspective view of a modified form of guiding means; Figure 9 is a perspective view of a still further modified form of guiding means which may be employed in the valve structure of my invention; Fig. 10 shows a modified construction of valve embodying my invention; Fig. 11 is a plan view of the armature and valve per se; and Fig. 12 is a cross-sectional view taken through the valve and armature of Fig. 11 on line 12—12 thereof.

My invention is directed to a construction of organ valve wherein the parts are extremely simple in their arrangements and assembly and in which substantially noiseless operation of the valve may be obtained. I provide a cup structure which may be centered in a supporting plate forming part of the valve structure, which cup structure is screw threaded to receive a valve seat against which the movable armature member is adapted to close. The armature member is confined in its movement to the space provided for such movement within the limits of the cup shaped retaining member which forms the housing for the armature. The armature is constituted by a circular plate of soft iron having an annular inturned edge which grips a fibrous sheet of material at the periphery thereof forming a padded face for one side of the armature which contacts with the adjustable valve seat forming an airtight closure.

Referring more particularly to the drawings, reference character 1 designates the electromagnet which may be of the horse-shoe type having poles 2 and 3 which enter recesses provided in the casting 4. The electromagnet carries electromagnet windings 5 which

are included in the control circuit. The plate member 4 is provided with an interior air passage represented at 6 which terminates in a port 7 at one side of the plate 4 and in the air passage formed through the adjustable valve seat 8 at the other side of the plate 4. The plate 4 is provided with a depending plug member 9 grooved at 10 to receive the latch 11. The latch 11 is pivotally mounted at 12 on removable plate member 15 and is provided with an actuating lug member 14. The plate member 15 carries a gasket 16 thereon which provides a seal between the plate 15 and the side walls of the chamber enclosed by plate 4. The plate 15 is canted in assembling the valve structure and engaged beneath the projecting member 17 carried by depending member 18. By canting the plate 15 and sliding it back in position beneath the projection 17 at one end and telescoping the plate over the extending lug 9 and thereafter latching the member 11 in the groove 10 it is possible to secure the plate 15 solidly in position with respect to the enclosure 6. The plate 15 is apertured and provided with a downwardly depending apertured annular portion 19 which receives the cup shaped member 20. Various forms of the cup shaped member 20 are shown more clearly in perspective view in Figs. 7, 8 and 9 wherein the member consists of an annular plate 20^a provided with upstanding dividing wall portions 20^b, each of which are segmental in contour and provide means for defining the path of movement of the armature member and permitting a free flow of air to exhaust when the magnet is energized and armature lifted from its seat, shown in Figs. 10 and 11. The armature member consists of a soft iron circular disc having a central portion 22 and an annular inturned edge 23 which is rolled over the fibrous material 24 which covers one side of the valve. The fibrous side of the valve seats against the annular periphery of the adjustable valve seat 8. The valve seat 8 is cylindrical in form and is exteriorly screw threaded as designated at 25 to engage the interior screw threads 26 within the cup shaped member 20. By adjusting the valve seat 8, the movement of the valve may be limited to the desired degree. The segmental wall members 20^b limit the movement of the valve laterally, while the longitudinal movement of the valve is controlled by the adjustment of the valve seat 8, the valve cushioning against the fibrous member 27 which lines the recess 6 within the plate 4 immediately around the tips of the magnetic poles 2 and 3. The fibrous member 27 is cemented or glued into the base 4 and is retained therein by the wall portions 20^b of the cup shaped member 20 which press upwardly against the member 27.

In Fig. 10 I have shown the plate 15 having a valve seat pressed directly thereupon

as represented at 36 forming an annular peripheral seat at 35 against which the valve disc rests. The guiding cup shaped member is shown having its flat portion 20^a surrounding the upstanding seat 35, with the wall portions 20^b extending upwardly from the portion 20^a.

The plate member 4 is provided with a gasket 28 which is arranged to seat against a hermetically sealed chamber with the port 7 connecting through the aperture 29 in the gasket 28. The gasket 28 is apertured at 30 around the offsets 32 and 33 in plate 4 and around the central portion 34 in plate 4.

It will be observed that the manufacture and assembly of the valve structure of my invention is extremely simple and that by virtue of the centering of the valve and the cushioning thereof the operation of the valve is substantially noiseless. The centering device may comprise diametrically opposed members, as illustrated in Fig. 7 or there may be three such members as shown in Fig. 8 or four independent outstanding segmental lugs may be provided as shown in Figure 9.

I have found the valve structure of my invention highly practical in its operation in securing silent valve control in organs where it is so important to prevent metallic clicks or noises from interfering with reproduced music.

While I have described my invention in certain of its preferred embodiments, I desire that it be understood that modifications may be made and that no limitations upon my invention are intended other than those imposed by the scope of the appended claims.

What I claim as new and desire to secure by Letters Patent of the United States is as follows:

1. In a valve for organs, a base member having a recess therein for the passage of air, an electromagnet having its poles projecting into said base member, with a port disposed in said base member between the poles of said electromagnet, a plate member closing one side of said base, a valve guide carried by said plate member in alignment with the poles of said electromagnet, an adjustable valve seat carried by said valve guide and an armature movable within said valve guide and engageable with said valve guide in one of its limiting positions, said armature being confined in its lateral movement by said valve guide.

2. In a magnetic valve for organs, a disc type valve, an electromagnet for controlling the movement of said disc type valve, and a valve guide for defining the lateral movement of said disc type valve, said valve guide comprising a member having a multiplicity of upstanding segmental lugs thereon surrounding said disc type valve for housing and controlling the disc type valve with respect to said electromagnet.

3. In a magnetic valve for organs, a base

member having a recess therein for the passage of air, an electro-magnet having its poles projecting into said base member, a closure for said recess in said base member, a device positioned within said closure in alignment with the poles of said electromagnet, said device comprising a laterally extending plate, a central depending cylindrical portion interiorly screw threaded to receive an adjustable valve seat and segmental portions upstanding from the periphery of said laterally extending plate, and a combined armature and valve positioned within said upstanding segmental portions and confined in its lateral movement by said upstanding segmental portions of said laterally extending plate.

4. In a magnetic valve for organs, a supporting base, an electromagnet, a magnetic disc valve arranged to be actuated by said electromagnet, a plate member closing one side of said supporting base, a valve seat struck from said base member, with an annular peripheral portion thereof extending upwardly into said supporting base, and a valve guide comprising a cup shaped member disposed concentrically about said upstanding valve seat for limiting the lateral movement of said magnetic disc valve.

In testimony whereof I affix my signature.

30 WILLIAM H. REISNER.

DISCLAIMER

1,769,966. *William H. Reisner*, Hagerstown, Md. VALVE FOR ORGANS AND THE LIKE. Patent dated July 8, 1930. Disclaimer filed March 31, 1934, by the patentee and the assignee, *The W. H. Reisner Manufacturing Co.*

Hereby enter this disclaimer to that part of the claims in said specification which is in the following words, to wit:

"1. In a valve for organs, a base member having a recess therein for the passage of air, an electromagnet having its poles projecting into said base member, with a port disposed in said base member between the poles of said electromagnet, a plate member closing one side of said base, a valve guide carried by said plate member in alignment with the poles of said electromagnet, an adjustable valve seat carried by said valve guide and an armature movable within said valve guide and engageable with said valve guide in one of its limiting positions, said armature being confined in its lateral movement by said valve guide."

"4. In a magnetic valve for organs, a supporting base, an electromagnet, a magnetic disc valve arranged to be actuated by said electromagnet, a plate member closing one side of said supporting base, a valve seat struck from said base member, with an annular peripheral portion thereof extending upwardly into said supporting base, and a valve guide comprising a cup shaped member disposed concentrically about said upstanding valve seat for limiting the lateral movement of said magnetic disc valve."
